UNITED STATES PATENT OFFICE

ARTHUR HITCHCOCK ORCUTT AND JOHN WILDSMITH SNARRY, OF BIRMINGHAM, ENGLAND, ASSIGNORS TO THE GEAR GRINDING COMPANY LIMITED, OF BIRMINGHAM, ENGLAND

GRINDING MACHINE AND OTHER MACHINE TOOL

Application filed January 16, 1929, Serial No. 332,965, and in Great Britain January 24, 1928.

This invention relates to grinding machines for grinding the teeth of gear wheels and for like purposes, and to other machine tools of the kind in which a reciprocating slide carrying the grinding wheel or other tool is mounted on a vertical guide.

The object of the invention is to provide improved means for holding the slide firmly in contact with the vertical guide.

10 The invention comprises the employment of a weight connected to the slide in such a manner that it holds the slide against the guide with substantially uniform pressure in all positions.

15 In particular the invention comprises the utilization of a balance weight for the double purpose of counterbalancing the weight of the slide and holding the slide against the guide.

20 Preferably the invention comprises the provision on the slide of a bell crank or other suitable lever, one end being attached by a chain or the like to a counter-weight and the other end connected by a radius rod to a stationary part of the machine, the arrangement being such that the counter-weight causes the slide to be held with substantially uniform pressure against the guide.

In the two accompanying sheets of ex-
30 planatory drawings:—

Figure 1 is a side elevation and Figure 2 a plan of a machine for grinding the teeth of gear wheels and provided with this invention.

35 In the example shown in the drawings, the vertical guide *a* consists of a suitably shaped surface and against this abuts a vertically reciprocating slide *b* carrying the grinding wheel *c*.

40 The weight of the slide is counter-balanced by a weight *d* which is attached to the slide by a rope *i* chain or the like passing over suitable guide pulleys *e*. In the arrangement illustrated a single rope passes over the two pulleys *e* mounted on the upper end of the machine and around a single pulley *f* on the weight. The connection between the two ends of the rope and the slide is effected by a pair of bell crank levers *g* pivoted coaxially on the slide. The rope is secured to one arm of

each of the levers, and the action of the weight thereon is such that it tends to rock the other arm in the direction away from the guide. The second arm of each lever is connected to the outer end of a radius rod *h* whose opposite end is pivoted to any suitable stationary part of the machine. Owing to the constraint exerted by the radius rod on the lever, the counter-weight, in addition to balancing the slide, also pulls the slide against the guide and so insures that the slide is held firmly against the guide in all positions. Obviously the same effect can be obtained by attaching a single end of a rope to a single bell crank lever on the guide. An advantage or convenience is afforded in the use of a double rope in that the pull on the slide can be exerted at two laterally separated points.

Alternatively, the rope or the like connected to the counter-weight may be connected directly to the slide in such a manner that it occupies an oblique position relatively to the slide and guide. The pull of the chain or the like then has two components, one vertical which counter-balances the slide, and the other horizontal which pulls the slide against the guide. In this arrangement the radius rod is not required.

If desired two independent weights may be used, one for counter-balancing the slide and the other for holding it against the guide.

By this invention we are able to adopt in machines provided with vertically reciprocating slides, slide and guide constructions which have formerly been used in high class machines having horizontally reciprocating slides, and the necessity for the slide retaining strips commonly employed in vertical machines is obviated.

Having thus described our invention what we claim as new and desire to secure by Letters Patent is:—

In grinding and other machine tools, the combination comprising a vertical guide, a slide movable on said guide, a bell crank lever pivoted on the slide, a balance weight, flexible means for securing the balance weight to one end of the bell crank lever, and a radius rod having one end attached to a fixed pivot,

the other end of the radius rod being attached to the other end of the bell crank lever, substantially as described.

In testimony whereof we have signed our
5 names to this specification.

ARTHUR HITCHCOCK ORCUTT.
JOHN WILDSMITH SNARRY.
